UNITED STATES PATENT OFFICE

EDWIN D. McCRACKEN, OF PATERSON, NEW JERSEY.

ELECTRO-MAGNET.

SPECIFICATION forming part of Letters Patent No. 314,041, dated March 17, 1885.

Application filed May 17, 1884. (No model.)

To all whom it may concern:

Be it known that I, EDWIN D. McCRACKEN, of the city of Paterson, in the county of Passaic and State of New Jersey, have invented 5 a certain new and useful Improvement in Electro-Magnets, of which the following is a specification.

In the making of electro-magnets it is of course of primary importance that the convolutions of wire of which the magnet is wound should be perfectly insulated from each other, and in very many kinds of electric apparatus—such, for example, as electric lamps and telegraph-instruments—it is a great advantage to 15 have the magnets as small in size as possible and consistent with the necessary strength.

The object of my invention is to provide an electro-magnet which shall have the convolutions of wire perfectly insulated, and which 20 for a given length and gage of wire shall be smaller than any magnet heretofore made in which the convolutions of wire were as perfectly insulated.

The invention consists in an electro-magnet 25 coil the wire of which is insulated by a spiral wrapping of paper.

The invention also consists in an electro-magnet formed of convolutions of wire having a covering consisting of a spirally-wound strip 30 or strips of pure vegetable paper, which forms of itself the insulating-covering of the wire.

In the accompanying drawings, Figure 1 is a sectional view of a magnet embodying my invention; and Fig. 2 represents a piece of the 35 insulated wire employed, the thickness of the wire and strips being greatly exaggerated to illustrate them more clearly.

Similar letters of reference designate corresponding parts in both figures.

40 A designates the spool, having heads *a a*, and on which the wire *b* is wound closely in the usual way. After winding the magnet an

outer envelope or covering, *c*, of vulcanized india-rubber, leather, or any other suitable material, is applied to give the magnet a finish 45 and to protect the wire. The wire *b* before being wound is covered with a thin insulation of paper made from pure vegetable fiber and applied in the form of a strip, *d*, wound spirally and lapped on itself about half its width. 50 If it is desired to obtain a thicker covering, a second strip, *d'*, of paper may be likewise applied, breaking joints with the first or previously-applied strip.

In applying the strip of paper I may employ 55 a thin solution of shellac or other adhesive substance laid onto the inner side of the strip; but in many cases the paper strip may be laid on tightly and spirally without any adhesive substance, the paper being very 60 slightly dampened with water before winding it.

For the spiral winding I employ very thin and tough paper, and when a single strip of paper is wound as described I obtain a double 65 thickness of paper throughout the wire, which will add but three or four thousandths of an inch to the diameter of the wire.

What I claim as my invention, and desire to 70 secure by Letters Patent, is—

1. An electro-magnet coil the wire of which is insulated by a spiral wrapping of paper, substantially as herein described.
2. An electro-magnet formed of convolutions of wire having a covering consisting of 75 a spirally-wound strip or strips of pure vegetable paper, which forms of itself the insulating-covering of the wire, substantially as and for the purpose herein described.

E. D. McCRACKEN.
